UNITED STATES PATENT OFFICE.

CHARLES SEYBOLD, OF DAYTON, OHIO.

PAPER-CUTTING MACHINE.

Application filed October 20, 1920. Serial No. 418,205.

To all whom it may concern:

Be it known that I, CHARLES SEYBOLD, a citizen of the United States, and a resident of the city of Dayton, in the county of Montgomery and State of Ohio, have invented certain new and useful Improvements in Paper-Cutting Machines, of which the following is a full, clear, and exact description, reference being had to the drawings forming part of this specification.

My invention relates to machines for cutting and trimming bundles or piles of paper and has particularly to do with improvements of the clamping mechanism in which the piles of paper are held with increasing frictional pressure as the cutting knife is drawn through the pile.

Heretofore, so far as I am aware, it has been customary to operate the clamp by a friction clutch interposed between the clamp, pulling bars and the driving power so that the clamp will compress the pile within the fixed limits of the friction clutch, which is designed to slip when the maximum pressure has been attained.

The quality of the paper stock dulls the knife and the time consumed to remove a dull knife for sharpening is an element of considerable moment in the working capacity of the machine, so that knives are apt to be kept in use until they can be no longer forced through the bundle of paper stock. It becomes of importance, therefore, in some cases to provide friction mechanism for the clamp which shall not be limited to any fixed amount but which shall automatically increase as the need for holding the pile increases during the cutting operation.

A dull knife itself acts as a clamp until it begins to cut so that the need for the compression of the pile increases as the knife passes through the paper stock.

It is the object of my invention to provide for this desired increase of the clamp pressure by increasing the speed of rotation of the clutch member in the manner and with the mechanism to be hereinafter particularly pointed out and claimed whereby the friction clutch elements are caused to travel with increased speed as the knife proceeds with its work.

In the drawings,

Figure 1 is a front elevation of one form of paper cutting machine with my improvements applied thereto.

Figure 2 is a front elevation of the invention in detail showing the working parts.

Figure 3 is a rear elevation of the same.

Figure 4 is a cross section taken on the lines 4—4 of Figure 2 looking in the direction of the arrow.

Figure 5 is a diagrammatic end view of the clamp.

The general construction of one form of paper cutter to which my invention is applied comprises the ordinary operating parts mounted in a solid substantial frame-work 1 with cutting table 2 and side standards 3, 3 for holding and guiding the knife carrier 4 and clamp 5. The knife carrier carrying the cutting knife 6 is actuated in the usual way by the pulling bars 7, 7 coupled to the main driving shaft 8 of the machine which is rotated by the driving pulley 9.

The paper clamp 5 is provided with side pulling arms which are coupled to a rock shaft 10 mounted in suitable bearings transversely of the machine so that with the rocking of this shaft the clamp is brought down upon the pile of paper to be cut. The rock shaft is actuated by connection with the knife driving shaft of the machine in the ordinary construction and a friction clutch connection provided between this driving shaft and the clamp rock shaft, so that the paper pile will be held during the cutting operation under the fixed tension of this friction clutch. This is the ordinary construction and it is to improve upon this construction that my invention is directed. The other details of construction of the paper cutter are not of importance and so far as shown are for illustrative purposes only.

In Figures 2, 3 and 4 I have shown the novel features of my present invention comprising the mechanism for frictionally connecting the knife drive shaft with the rock shaft for the clamp to obtain automatically increasing pressure of the clamp as the knife proceeds with its work.

Keyed to the drive shaft 8 is an eccentric 12 carrying the eccentric strap 13 which is split as usual for mounting and the halves held together by the clamp bolts 14, 14. Formed on the eccentric strap is a boss 15 into which is screwed a link arm 16, the outer end of which is pivoted at 17 to a rocker arm 18 which is loosely mounted on the rock shaft 10. The link arm 16 is pivoted to the rocker arm about mid-way of its

length and the outer end of the rocker arm is provided with a bearing in which is mounted a hollow shaft 19 through which passes a shaft or rod 20 threaded at each end and provided with nuts 21, 21.

Keyed to the rock shaft 10 on each side of the rocker arm 18 are segment gears 22 and loosely journaled on the hollow shaft 19 are a pair of pinions 23, 23, which engage the 10 segment gears on the rock shaft 10, while keyed to the hollow shaft 19 between the pinions is a ratchet wheel 24 which is engaged by a pawl 25 pivoted at 26 to the rocker arm 18 and which prevents the 15 ratchet from any back movement while permitting free movement in the opposite direction. The pawl is held in engagement with the ratchet by the spring 27 mounted in the housing 28. Keyed to the hollow shaft 19 20 are friction clutch members 29 having six cup shaped recesses for the reception of coiled springs 30, the outer ends of which are secured to the disks 31, also keyed on the hollow shaft. The clutch members are thus 25 held by these springs in frictional engagement with the leather disk washers 32 carried by the side faces of the loosely mounted pinions and any desired frictional tension may be obtained by tightening the nuts 21 30 on the screw threaded ends of the rod 20 which bear upon the disks 31.

In order to prevent too great a tension being obtained, the hollow shaft 19 is extended a slight distance beyond the tension 35 members 29 so as to form a shoulder 33 at each end and prevent tightening up the disks 31 beyond a fixed point. It will be understood from the foregoing that the pinions 23, 23 are thus frictionally secured to the hollow shaft and the ratchet wheel but that the pinions which are in engagement with the segment gears 22 can slip under the tension of the clutch members as the rocker arm 18 is carried its full stroke under the action 45 of the eccentric 12 on the driving shaft 8.

The segment gear 22 is provided with a lug 34 which normally lies in engagement with a corresponding lug 35 on the rocker arm 18 and as the segment gears 22 are 50 keyed to the rock shaft 10 and this rock shaft is coupled to the pulling arms of the clamp, as the rocker arm is swung by the eccentric the teeth of the pinions 23 carry the segment gears by pushing on them and thus rock the shaft 10 and bring the clamp down to the paper pile. As soon as the clamp meets the pile and is stopped in its 55 downward movement the tension between the pinions 23 and the hollow shaft 19 is exerted to compress the paper pile. As soon as the limit of tension is reached inasmuch as the ratchet can not rotate being held by the pawl 25, the pinions begin to rotate, maintaining the compression and the lugs 60 34 and 35 separate, the rocker arm continu-

ing its stroke, and the segment gears ceasing to rock. The compression of the clamp is therefore maintained during the cutting operation of the knife, and as the distance from the center of the rock shaft 10 to the pulling 70 arms of the clamp is very much less than the distance from the rock shaft to the hollow shaft (in the present instance 1 to 2), when the frictional tension is applied a frictional tension of 1000 pounds will give a compression of 2000 pounds. On the return stroke of the rocker arm the ratchet is released by the pawl and the ratchet, hollow shaft and pinions rotate back to normal, the lug 35 on the rocker arm picks up the lug 34 on the segment gear and the rock shaft 10 is rocked back to its normal position lifting the clamp to its raised position and releasing the paper pile. While the friction clutch remains constant the actuation of the rocker arm by the eccentric causes the rocker arm to increase its speed to the middle of its stroke and then gradually to decrease. This increase of speed proportionally increases the clutch pressure as the knife enters the paper pile 80 and therefore the compression exerted by the clamp increases as the knife enters the pile. 90

To prevent any overthrow of the rock shaft in lifting the clamp I provide a band brake 36 engaging a pulley on the rock shaft 10 which is regulated by spring tension bolt 37. 95

Having thus described my invention, what I claim as new and desire to secure by Letters Patent, is:— 100

1. In a paper cutter, the combination with the knife driving mechanism and a rock shaft for actuating the clamp, of means for rocking the shaft comprising a member fixed thereto and a member loosely mounted thereon in engagement therewith, a friction clutch for the loosely mounted member and means for actuating said member to rock the clamp actuating shaft and actuate the clamp in both 105 directions. 110

2. In a paper cutter, the combination with the knife driving mechanism and a rock shaft for actuating the clamp, of means for rocking the shaft comprising a member fixed thereto and a member loosely mounted thereon in engagement therewith, a friction clutch for the loosely mounted member and an eccentric for swinging the loosely mounted member positively in both directions to bring the clamp into action and to actuate the 115 clamp in both directions. 120

3. In a paper cutter, the combination with the knife driving mechanism and a rock shaft for actuating the clamp, of means for rocking the shaft comprising a segment gear fixed thereto and a rocker arm loosely mounted thereon, a pinion mounted on the rocker arm in engagement with the segment gear with a friction clutch interposed between the 125 130

pinion and gear and means for swinging the rocker arm to bring the clutch into action and to actuate the clamp in both directions.

4. In a paper cutter, the combination with
5 the knife driving mechanism and a rock
shaft for actuating the clamp, of means for
rocking the shaft comprising a segment gear
fixed thereto and a rocker arm loosely mount-
ed thereon, a pinion mounted on the rocker
10 arm in engagement with the segment gear
with a friction clutch interposed between the
pinion and gear and an eccentric for swing-
ing the rocker arm its full stroke to increase
the clutch action.
- 15 5. In a paper cutter the combination with
a driving shaft for the knife and a rock shaft
for the clamp, of a segment gear keyed to the
rock shaft, a rocker arm loosely mounted on
the rock shaft, a pinion mounted on the
20 rocker arm in engagement with the segment
gear, means for normally locking the gear
from rotating and a friction clutch inter-
posed between the pinion and the locking
means, with means for actuating the rocker
25 arm its full stroke under the tension of the
clutch when the clamp reaches the paper
pile.

6. In a paper cutter the combination with
a driving shaft for the knife and a rock shaft

for the clamp, of a segment gear keyed to the 30
rock shaft, a rocker arm loosely mounted on
the rock shaft, a pinion mounted on the
rocker arm in engagement with the segment
gear, a pawl and ratchet for normally lock-
ing the gear from rotating and a friction 35
clutch interposed between the pinion and the
ratchet with an eccentric for actuating the
rocker arm its full stroke under the tension
of the clutch when the clamp reaches the
paper.

7. In a paper cutter the combination with
a driving shaft for the knife and a rock shaft
for the clamp, of a segment gear keyed to 40
the rock shaft, a rocker arm loosely mounted
on the rock shaft, a pinion in engagement
with the segment gear, a hollow shaft jour-
naled in the rocker arm upon which said
pinion is loosely mounted, a ratchet keyed to
the hollow shaft with pawl on the rocker arm
to lock same from movement in one direction 45
and friction clutch members intermediate
the pinion and the hollow shaft, an eccentric
on the knife driving shaft and link connec-
tion therefor, with the rocker arm whereby
the swinging of the rocker arm will cause 50
said pinion to rock the clamp rock shaft
under the tension of the friction clutch.

CHARLES SEYBOLD.
